UNITED STATES PATENT OFFICE.

THOMAS LAMBETH, OF RACHEL, NORTH CAROLINA.

FOLDING CHAIR.

1,162,618.

Specification of Letters Patent. Patented Nov. 30, 1915.

Application filed October 3, 1914. Serial No. 864,771.

To all whom it may concern:

Be it known that I, THOMAS LAMBETH, a citizen of the United States, residing at Rachel, in the county of Randolph and State of North Carolina, have invented certain new and useful Improvements in Folding Chairs; and I do hereby declare the following to be a full, clear, and exact description of the invention, such as will enable others skilled in the art to which it appertains to make and use the same.

This invention relates to folding chairs of the class wherein the seat and fore legs fold against the back.

My object is to provide a comfortable, strong and durable chair, easy of operation and of moderate cost.

In the drawings herewith which are made a part of this application Figure 1 is a side elevation. Fig. 2 is a plan view of the bottom of the chair revealing the locking mechanism. Fig. 3 is a fragmental vertical sectional view on the line 4—4 in Fig. 2. Fig. 4 is a perspective view of the notch into which the latch moves. Fig. 5 is a plan view of the notch on the lines 5—5 of Fig. 4.

In referring to the drawing in detail, numerals will be used to indicate the various parts and the same numeral will be used to indicate the same part throughout the various views there shown.

The chair comprises three principal parts; the rear frame 1, the front frame 2 and the seat 3, and the means for bracing and holding the parts of the chair in rigid operative relation to each other. These various parts will be specifically described hereinafter.

The back frame 1 comprises two upright standards of sufficient length to form the rear legs 6 and the back supports 7 integrally, having the usual rungs and cross slats occurring in frame chair construction.

The front frame 2 comprises two legs 8 of suitable length to support the seat 3 at proper height, being connected adjacent the lower end thereof by an ordinary wooden rung. At the upper end near the extremity thereof the front legs are connected by a cross piece 9 rectangular in cross section, positioned so that the widest dimension thereof is presented frontwardly and rearwardly. On the top edge of said cross piece, a cap piece 10 is secured, the rear edge thereof being flush with the rear face of the said cross piece, while the front edge extends

a short distance beyond the front face thereof, the upper face of said cap piece being adjacent the top ends of the front legs 8 and a short distance below the said top ends. In the said cross piece 9, in its upper edge and adjacent each end thereof, elongated notches 11 and 11^a are cut, the inner end 12 of the notch 11 being cut concave. In the lower and rearward part of the notch 11 a portion 13 of the material is left, the end 14 of which is rounded to conform to the concave portion 12. The said portion 13 forms a holding member for the latch hereinafter described. The notch 11^a is formed identical with the notch 11.

The seat 3 comprises a square frame hingedly mounted upon the rear frame by strap hinges 15 and furnished with a covering of any preferred material.

Pivotedly connecting the front and rear frames are two metal rungs 16 on each side of the chair. The said metal rungs, when in normal position, extend parallel to the plane of the seat when said seat is in its normal position and also parallel to each other. Connecting the two frames are two lateral braces, one of said braces comprising a member 17 shaped substantially as an elongated U, and two bars 18, the other of said braces comprising two bars 19 and a U-shaped body portion 17^a similar to 17 except that the part connecting the ends thereof is shorter than that of the member 17. The members 17 and 17^a have their ends bent to form eyes 20. The bars 18 and 19 have one end bent to form an eye 21 and the opposite end bent at a right angle to the body portion. The U-shaped member 17 is secured to the legs of the front frame by means of staples 22, the second U-shaped member 17^a being secured to the legs of the rear frame in the identical manner as the member 17 is secured to the legs of the front frame. The two bars 18 are positioned on the U-shaped member 17 by means of the eyes 21, turned on the ends thereof, engaging the cross bar of said U-shaped member adjacent the ends thereof. Each of said bars 18 connects the U-shaped member 17 with a rear leg a short distance above the seat 3.

The bars 19 are secured to the U-shaped member 17^a in an identical manner and in the same relative position thereon as the bars 18 are secured to the member 17, the bent portion of these bars 19, however, be-

ing pivotedly secured to the under side of the seat adjacent the front edge thereof by means of retaining plates 23 and 23^a.

When the braces just described are in operative position they form a cross jointed at the center, the two parts of the members 17 and 17^a connecting the side portions thereof, being parallel to each other, the rods 19 being positioned between the rods 18. The retaining plates 23 and 23^a hold in operative position the bars 19 and also the latches 24 and 24^a. The said latches are pivoted to the retaining plates 23 and 23^a and are provided with flanges 25 and 25^a on the rear edges thereof to be grasped when operating the latches. Flanges 26 and 26^a are provided on the front edges thereof, said latter flanges 26 and 26^a being intended to enter the notches 11 and 11^a on the front frame and engage the portion 13 thus locking the seat to the front frame, uniting the movable parts into a firm and substantial whole when the latches are in position in the said notches. To fold the chair, the latches are removed from the slots by turning them on their pivots. The front frame is then grasped and raised toward the back frame, while the seat simultaneously and automatically descends against the lower part of the back frame through the action of the jointed braces 17 and 17^a.

While I have described in the foregoing specifications and illustrated in the accompanying drawings the preferred construction and combination of parts deemed necessary in materializing my invention, I desire it to be understood that I wish to comprehend in this application all substantial equivalents and substitutes which may be considered as falling fairly within the scope of my invention and I do not therefore wish to be confined strictly to the exact showing herein presented.

Believing that the construction and com-

bination of parts and the manner of using my invention have been made clearly apparent, further description is deemed unnecessary.

Having thus fully described my invention, what I desire to secure by Letters Patent, is:

1. A chair of the class described, comprising a front frame having notches therein, the inner ends of which are curved, a holding member extending upwardly in each notch and having a curved face, a rear frame, a seat hingedly mounted upon the rear frame, latches pivotally mounted upon said seat and having depending flanges adapted to enter said notches to engage the curved faces of the holding members and pivotally mounted rungs connecting the legs of the front and rear frames.

2. A chair of the class described, comprising a front frame, a rear frame, a seat hingedly mounted upon the rear frame; latches mounted upon the said seat member; engaging notches in the front frame; pivotally mounted rungs connecting the legs of the front and rear frames.

3. A chair of the class described comprising a front frame; a rear frame; a seat member hingedly mounted on the rear frame; latches mounted on the said seat member; engaging notches in the front frame; pivotally mounted rungs, connecting the legs of the front and rear frame; jointed lateral cross braces joining the front edge of the seat member to the rear frame, and other jointed lateral cross braces joining the front and rear frames.

In testimony whereof I have signed my name to this specification in the presence of two subscribing witnesses.

THOS. LAMBETH.
